(57) **CLAIM**

The ornamental design for a car-shaped shoe, substantially as shown and described.

DESCRIPTION

FIG. 1 is a top view of the car-shaped shoe of the present invention;

FIG. 2 is a first side view of the car-shaped shoe;

FIG. 3 is a bottom view of the car-shaped shoe;

FIG. 4 is a second side view of the car-shaped shoe;

FIG. 5 is a front view of the car-shaped shoe; and,

FIG. 6 is a rear view of the car-shaped shoe.

The broken line showing of the sole is included for the purpose of illustrating environmental structure and forms no part of the claimed design.
